UNITED STATES PATENT OFFICE

159,668

PUPPET DOLL

Friedrich Schleich, Schwabisch, Gmund,
Germany

Application April 5, 1949, Serial No. 1,820
In France April 1947

Term of patent 14 years

(Cl. D34—4)

To all whom it may concern:

Be it known that I, Friedrich Schleich, a German citizen, residing in Schwabisch Gmund, Germany, have invented a new, original, and ornamental Design for a Puppet Doll, of which the following is a specification reference being had to the accompanying drawing, forming part thereof. Fig. 1 is a perspective view of the puppet doll showing my new design, and

Fig. 2 is a rear perspective view of the doll shown in Fig. 1.

Fig. 3 is a side elevation view of the doll shown in Fig. 1.

I claim:
The ornamental design for a puppet doll, as shown.

FRIEDRICH SCHLEICH.
